UNITED STATES PATENT OFFICE.

JAMES HANNAN, OF MUSCATINE, IOWA.

TOY CANNON AND TARGET.

SPECIFICATION forming part of Letters Patent No. 569,282, dated October 13, 1896.

Application filed January 30, 1896. Serial No. 577,414. (No model.)

To all whom it may concern:

Be it known that I, JAMES HANNAN, a citizen of the United States, residing at Muscatine, in the county of Muscatine and State of Iowa, have invented a new and useful Toy Cannon and Target, of which the following is a specification.

This invention relates to an improvement in toys, and has for its object to provide a miniature toy cannon and target mounted upon a common base, the cannon being adapted to project a ball in the direction of the target.

A further object of the invention is to provide in connection with the cannon means whereby a percussion-cap may be exploded simultaneously with the firing of the ball.

With the above objects in view the invention consists in certain novel features and details of construction and arrangement of parts, as hereinafter fully described, illustrated in the drawings, and finally pointed out in the claims.

In the accompanying drawings, Figure 1 is a perspective view of the improved toy complete. Fig. 2 is a longitudinal sectional view through the barrel of the cannon, showing the spring-plunger, &c. Fig. 3 is a detail perspective view of the cap-socket. Fig. 4 is a detail view of the pivoted target. Fig. 5 is an enlarged detail perspective view of the trigger mechanism.

Similar numerals of reference designate corresponding parts in the several figures of the drawings.

Referring to the accompanying drawings, 1 designates a board of any suitable length constituting the base upon which the other parts of the toy are mounted. At one end of this base-board is rigidly attached a stationary gun rest or carriage 2, the inner portion of which is provided, as to its top edge, with a groove forming a longitudinal seat for a section of metal tubing constituting the barrel 3 of the cannon. The rear portion of the gun-rest is cut away or depressed for convenience in mounting the trigger herein-after described.

Within the breech of the barrel is fitted a rigid breech-plug 4, having an eccentric perforation 5, through which passes a plunger 6, having a cap or ferrule 7, attached to its front end and approximating the internal

diameter of the barrel 3. A spiral spring 8 is interposed between the cap or ferrule 7 and the breech-plug 4, which spring serves 55 to actuate the plunger toward the muzzle of the barrel. Adjacent to its rear end the plunger is provided with a finger-grasp 9, by means of which the said plunger may be retracted, and also has a loop or eye 10 for engagement with the trigger, (indicated at 11.) This trigger may be formed from a piece of wire, the front end of which is driven into the rest 2, from whence it extends rearwardly 60 in a groove in said rest, being formed with a vertical catch 12 for engaging the eye 10 on the plunger, and also having a rearwardly-extending trip-arm, by means of which the trigger may be manipulated both for engaging and releasing the plunger. The trigger 70 may be made from spring-wire, so that its engagement with the plunger will be normally preserved. The plunger is also provided adjacent to its rear end with a lateral extension forming a hammer 13, the end of which is 75 preferably arranged in the same horizontal plane as the plunger proper, but at one side thereof, the said hammer being adapted, in the forward movement of the plunger, to strike against and explode a percussion cap 80 or pellet contained in a metal socket-piece 14, arranged at the breech of the barrel 3. This cap-socket is made from a piece of sheet metal, the same being folded upon itself so as to leave a sufficient amount of space between the folded portions to admit of the insertion of a percussion-cap.

The rear folded portion of the cap-socket is provided with a notch 15, through which the hammer operates in exploding the cap. The 90 cap-socket fits and slides, as to its lower edge, in a transverse groove 15^a in the upper surface of the gun-rest 2, and its inner end is slotted to straddle the plunger-stem 6. The socket 14 is extended at its outer end to form 95 a finger-hold by which it may be removed and replaced, and a cord is interposed between the cap-socket and gun rest or base to prevent the former from being lost. The cap-socket may be secured to the gun-rest in any 100 convenient manner. At the opposite end of the base 1 is arranged a rigid upright stop 16, consisting of a board or plate having its central portion cut out and a pivoted block or

movable bull's-eye 17 arranged therein and journaled on a horizontal pin or wire 18 at or near the base of said block. This pivoted block may have represented thereon a head, 5 as illustrated in the drawings, although it will be apparent that any desired representation may be made thereon, or an audible target in the form of a gong may be attached either to the block or the stop. This target is located 10 within the range of the cannon and is adapted to be operated by means of a captive ball 19, fast upon the end of an anchoring-cord 20, or a ball not so fastened, if desired.

In operation the plunger is drawn back and 15 engaged by the trigger in the manner above described, a percussion-cap being thereafter inserted in the cap-socket at the breech of the barrel. The ball is now placed in the muzzle of the barrel and pushed toward the 20 breech by means of a ramrod, when the cannon is ready to be fired. This is accomplished by manipulating the trigger, which releases the plunger and causes the ball to be projected toward and against the target. The 25 stop-board surrounding the pivoted target stops the balls in the event of their going wide of the mark, thus adding to the safety of the device.

The toy hereinabove described may be manufactured at slight cost and will be a source of 30 much amusement and entertainment to children, especially as the simultaneous explosion of the percussion-cap adds to the realistic effect.

35 Changes in the form, proportion, and minor details of construction may be resorted to

without departing from the spirit or sacrificing and of the advantages of this invention.

Having thus described the invention, what is claimed as new is—

1. The herein-described toy comprising a cannon having a tubular barrel, a reciprocating spring-actuated plunger therein, a trigger for said plunger, a hammer carried by and forming a part of the plunger, and a cap-socket 45 located near the breech of the barrel, the said cap-socket being slotted to engage the plunger-stem and formed to constitute a holder for a percussion-cap, substantially as described.

2. The herein-described toy, comprising a tubular barrel, a rest in which said barrel is seated provided with a transverse groove or recess, a reciprocating spring-actuated plunger within the barrel and extending in rear of 55 the breech thereof and provided near its rear end with a laterally-disposed hammer forming a part of the plunger-stem, and a detachable cap-socket fitted in the transverse groove of the rest, the said cap-socket being provided 60 with an aperture through which the plunger-stem reciprocates and also provided in its rear face with a notch for exposing a percussion-cap to the action of the hammer, substantially as described.

In testimony that I claim the foregoing as my own I have hereto affixed my signature in the presence of two witnesses.

JAMES HANNAN.
